tion of Ohio

Original application March 2, 1940, Serial No.
321,817, now Patent No. 2,442,414, dated June
1, 1948. Divided and this application May 14,
1947, Serial No. 748,033

15 Claims. (Cl. 158—37.4)

1

This invention relates to blowpipes and particularly to improved blowpipe heads and a method of making the same.

This application is a division of my copending application Serial No. 321,817 filed March 2, 1940, now Patent No. 2,442,414.

Hand-deseaming blowpipes are used for thermochemically removing defective surface portions of steel ingots, billets, blooms and the like which, unless removed, cause imperfections or blemishes in the finished-rolled product. When deseaming steel articles, at least a portion of the work surface is preheated to the oxygen ignition temperature and a relatively voluminous oxidizing gas jet is applied obliquely against and along successive portions of the metal surface so preheated to react thermochemically with and remove metal from said surface. Hand-deseaming blowpipes employed for this purpose include a nozzle having a relatively large central cutting-oxygen passage extending therethrough and having a plurality of relatively small preheating gas passages substantially parallel with and usually disposed circumferentially about the cutting oxygen passage. The blowpipe is held so that the longitudinal axis of the nozzle is at an acute angle to the surface of the workpiece and the blowpipe is pushed along the workpiece in the general direction of the oxidizing gas stream issuing from the nozzle. Guidance of the blowpipe by slidingly contacting the nozzle end with the metal surface is desirable when hand-operated deseaming blowpipes are moved along the surface to be deseamed as the nozzle and the jets discharging therefrom may then be more readily maintained constantly at the correct acute angle with the surface of the workpiece.

A blowpipe head is subject to damage by heat, oxidation, abrasion, and from other sources which shorten the useful life of the blowpipe. The life of a hand-deseaming blowpipe particularly is relatively short as the blowpipe head is close to or in actual sliding contact with the heated work surface in a zone of high temperature heat and oxidizing gas. In addition, the life of such blowpipes is shortened further by operators using the blowpipe head as a scraper to remove fins and other deposits from the work surface by briskly rubbing the head back and forth across the work.

Accordingly, an object of this invention is to

2

provide a blowpipe head having an outer protecting and reinforcing layer or shield of abrasion-and-heat resistant metal to increase the useful life of the blowpipe.

Other objects of this invention include the provision of a blowpipe head that is light in weight to reduce the effort involved in manipulating the blowpipe; and the provision of a blowpipe head that is essentially of a unitary construction and economical to manufacture.

The above and other objects and novel features of this invention will become apparent from the following specification and the accompanying drawing, in which:

15 Fig. 1 is a longitudinal sectional view of a blowpipe head showing one embodiment of the invention;

Fig. 2 is a sectional view taken along the line 2—2 of Fig. 1;

20 Figs. 3 and 4 are longitudinal sectional views of blowpipe heads showing other embodiments of this invention; and

Fig. 5 is a sectional view taken along the line 5—5 of Fig. 4.

25 The principles of this invention may be embodied in any cutting or deseaming blowpipe head. Referring more particularly to Figs. 1 and 2, the principles of this invention are shown as being embodied in the head H of a conventional hand-

30 operated deseaming blowpipe, such as is disclosed in United States Patent No. 1,957,351 to Samuel R. Oldham, May 1, 1934. The head H is adapted to operatively receive a deseaming nozzle N, which is removably retained in the head by a nut T. A

35 gas passage P is formed in the head H, and has smooth, continuous walls and is so curved that it does not abruptly change the direction of gas flow. Partially encircling the head H is a protecting metal layer or shield S of a suitable alloy, such as an alloy consisting of 35 per cent of metal from the group consisting of chromium, molybdenum, and tungsten, the remainder principally comprising metal from the group consisting of iron, nickel, and cobalt, which alloy is

40 resistant to abrasion, deformation and oxidation at high temperatures.

Prior to casting the body portion 10 of head H, a properly shaped core of a suitable material or a treated core such as a core coated with graphite, or other finely-divided material, may

be placed in the mold to form the passage 11 having a smooth, continuous curved wall which is not rough as is the surface of the usual sand casting.

It is preferable, but not necessary, that the cored passage 11 extend entirely through the casting. The inlet end of passage 11 is enlarged at 13 to receive an end portion of the blowpipe cutting oxygen supply tube 14, which is secured thereto by silver solder or other suitable means. The outlet end of passage 11 is enlarged to provide a socket 15, to operatively receive the inlet end of the deseaming nozzle N. Seating surfaces 16 and 17 are provided in socket 15 which are engaged by corresponding seats on the rear end of the nozzle N. Nozzle N is removably secured to the blowpipe head by means of the nut T which threadedly engages the internally threaded portion 19 of the socket 15. The inner end of nut T engages the underside of a shoulder 18 on the nozzle to retain the nozzle in the socket, and to tightly press the seats on the nozzle against the surfaces 16 and 17 to hermetically seal these joints.

The body 10 also contains a combustible gas passage 20 communicating with cavity 21 and adapted to receive the end of combustible gas conveying tube 22 which may be fastened therein by silver solder or other suitable means. Passage 20 has an outlet orifice discharging into a chamber 23 between the seating surfaces 16 and 17.

In nozzle N there are a plurality of preheating gas passages 25 usually disposed substantially parallel to the central cutting oxygen bore 26. The preheating gas passages 25 have inlet ori-fices 27 opening into the chamber 23. The seating surface 16 and the corresponding seat on the nozzle form a gas-tight seal to prevent cutting oxygen from escaping from passage 11 into chamber 23, and the seating surface 17 and the corresponding nozzle seat form a gas-tight seal preventing the escape of combustible gas to the atmosphere.

The cutting oxygen is supplied to tube 14 through the usual control valve of the blowpipe (not shown) and flows from tube 14 through passage 11 and the central bore 26 of nozzle N to the nozzle outlet orifice 28. As shown in Fig. 1, the longitudinal axis of the nozzle bore 26 is at approximately an angle of 70 degrees to the axis of the oxygen supply tube 14, and passage 11 is gradually curved and has a smooth, continuous wall.

The combustible gas mixture of oxygen and acetylene is supplied to tube 22 from an appropriate mixer in the blowpipe (not shown) and flows from tube 22 through passage 20, distributing chamber 23 and the preheating gas passages 25 of nozzle N and against the work to provide a flame of sufficient intensity to raise that portion of the surface against which the cutting oxygen impinges to the oxygen ignition temperature.

Blowpipe heads are made of corrosion-resistant, machinable cast metal, usually bronze, which is not as resistant to abrasion, corrosion, and deformation at high temperatures as some other alloys, such as those containing chromium and tungsten commonly known to the trade as "Stellite." The last-mentioned abrasion-resistant type of alloy or hard-surfacing metal is so hard that it is very difficult, if not impossible, to machine it. To manufacture economically a blowpipe head which will have a long life, a head preferably is formed of two metals or alloys, 75 and other deposits from the work surface by

i. e., a body of a corrosion-resistant relatively easily machined metal such as bronze and a protecting shield of an alloy which is relatively hard and difficult to machine but is resistant to corrosion, abrasion and deformation when subjected to high temperatures.

The improved reinforcing and protecting shield S is permanently secured to and extends around the major part of the body 10. The shield S preferably is cast onto the body 10 to provide a unitary head, as by placing the body 10 in a suitable mold and pouring abrasion-resistant molten metal into a mold cavity partially encircling the body. The body 10 contains a much larger volume of metal than the shield S so that body 10 acts as a chill block to aid in quickly solidifying the molten metal to form the shield S, as shown in Figs. 1 and 2.

While the cast-in-place shield S adheres to some extent to body 10, the two metals do not alloy so that there is no chemical bond to rigidly hold the shield in place. Bronze melts at around 1750 degrees and the abrasion-resistant metal melts at around 2400 degrees. The comparatively large volume of metal in body 10 so quickly chills the molten metal of shield S that there is no appreciable melting of the bronze and mixing of the metals. However, it is undesirable for the molten metal to melt the bronze casting. The body 10 is made light in weight and with comparatively thin walls to reduce the weight of the blowpipe and lessen the fatigue of the operator, and if the hard-surfacing metal did melt the bronze, the walls of the passages therein, particularly passage 11, might be melted through and thus ruin the head. Therefore, the shield S and head H are preferably so designed that the shield will be mechanically retained in place on body 10 to protect the head H and especially to protect that portion of the head which comes in contact with or adjacent to the surface of the workpiece. As shown in Figs. 1 and 2, the shield is generally U-shaped in cross section so that the portion corresponding to the bend of the U completely covers the front surface of the body 10, while the parts corresponding to the limbs of the U extend more than halfway around body 10, so that the shield S grips the body 10 and is mechanically retained in place thereon.

To reduce further the weight of the head H, the rear portion of body 10 is formed with flat side walls, as more clearly shown at 12 in Fig. 2. As an additional aid for retaining the reinforcing shield in place, a transverse hole 30 is drilled through body 10, and when the molten abrasion-resistant metal is poured about body 10, some molten metal will flow into passage 30 and fill it to form a portion or pin 31 integral with and connecting the two sides of the shield S. It is obvious that instead of filling the hole 30 with molten metal or otherwise uniting the two sides of the shield to one another and to the body 10, the sides of the shield S may be extended farther around the body 10, but this would add useless weight and increase the cost, without materially increasing the life of the blowpipe head. A rivet may be employed to unite the two sides of the shield but the integral connection is preferable.

The shield S reinforces the blowpipe head and prevents damage thereto when the head is adjacent the work in a zone of high temperature heat and oxidizing gas and also when the operator uses the head as a scraper to remove fins

rubbing the head back and forth across such surface. The shield S may be provided with an outwardly projecting lip or shoe 33 which may extend all or part way around the lower end of the head adjacent the nozzle socket. The shoe 33 may be used as a scraper in removing fins or other surface deposits and, since it is of wear-resistant metal and considerably thicker than the rest of the shield S, the life of the blowpipe head will be further prolonged by this shoe.

The nozzle N preferably is provided with an abrasion-resistant metal ring 34 permanently secured to and projecting outwardly from the front end of the nozzle, for contacting the work surface to aid in guiding and positioning the nozzle. The thickness or height of both the shoe 33 and the ring 34 may be so proportioned and located that when the operator places the blowpipe on the work with shoe 33 and ring 34 contacting the work surface, the longitudinal axis of the oxygen passage 26 of nozzle N is at the correct acute angle to the work surface for most efficiently removing metal. By having two points contacting the work surface, the operator can more readily maintain the blowpipe in the correct position while moving it along the surface. If nozzle N is not formed with a protecting ring the front end of the nozzle will be quickly worn away, thereby ruining the nozzle and causing the blowpipe to be incorrectly positioned. By forming the ring 34 and the shield S of abrasion-resistant material the life of the blowpipe is greatly increased, and by correctly proportioning the shoe 33 and ring 34 the period during which the blowpipe can be correctly positioned by contacting both the shoe 33 and ring 34 with the surface is greatly increased.

Referring more particularly to Fig. 3 of the drawings, prior to casting the body 10, a tube 35, which may be of suitable metal such as copper, is placed in the mold and the mold is then filled with molten bronze or other relatively machinable corrosion-resistant metal. The tube 35 may extend through and project beyond both the rear and front ends of the body casting 10, as shown by broken lines at 36 and at 37. The projecting end 36 of tube 35 is then severed and a portion of tube 35 and casting 10 is removed by drilling to form a cavity 38 into which there is gas-tightly secured the end of the oxygen supply tube 14 as by silver solder. The other projecting end portion 37 of tube 35 may be removed and a cavity 39 bored in body 10 for operatively receiving a blowpipe nozzle N.

The tube 35 has the proper diameter and preferably is gradually and smoothly curved, as shown, before being placed in the mold so that the resulting cutting oxygen passage 40 formed in the head by the tube will have smooth, continuous walls and is so curved that it will not abruptly change the direction of gas flow. The oxidizing gas flows from tube 14 through passage 40 to the oxygen bore 26 extending through nozzle N and the turbulence, friction and loss of velocity is reduced to a minimum.

Except for the means of forming passage 40, the head of Fig. 3 is generally similar to that of Fig. 1.

Referring to Figs. 4 and 5 of the drawings, when the body 41 is cast, two smooth surface cores are placed in the body mold to form the cutting oxygen and combustible gas passages 42 and 43, respectively. In this blowpipe head the position of the blowpipe tubes is such that the cutting oxygen tube 14 is below the combustible

gas tube 22. The core for forming cutting-oxygen passage 42 is formed with a gradual reverse curve to bring the outlet portion of passage 42 substantially axially in line with the cutting-oxygen bore 26 in the blowpipe nozzle. The inlet end of passage 42 is enlarged at 43 for receiving the end of the cutting oxygen supply tube 14 which is fastened therein, as by silver solder. The outlet end 44 of passage 42 is enlarged and adapted for operatively receiving the rear end of a blowpipe nozzle N.

The cutting oxygen flows from tube 14, through gradually curved passage 42, through the central bore 26 of nozzle N and out the outlet orifice 28 onto the work. Passage 42 has a smooth, continuous wall and is gradually curved so that the oxygen stream does not become turbulent which would reduce the cutting efficiency of the jet.

When body 41 is cast, a second smooth-surface core is placed in the mold to form the gradually-curved combustible gas passage 43. The passage 43 is formed with an oblong cross section as shown in Fig. 5, to reduce the weight of the head H. If passage 43 were formed with a circular cross-section and with the same cross-sectional area the wall 45 would have to be thicker which would increase the weight of the head H.

The inlet end of passage 43 is enlarged as at 46 to receive the end of the combustible gas supply tube 22 which is fastened in place, as by silver solder. The outlet end of passage 43 opens into the enlarged portion 44 of passage 43 between the seats 16 and 17. The combustible gas flows from tube 22, through passage 43, into the chamber 46 between the walls of cavity 44 and the nozzle, and from chamber 46 through the preheating passages 25 in nozzle N. Passage 43 has a smooth, continuous wall and is so curved that it does not abruptly change the direction of gas flow so that no undue turbulence or friction is caused to reduce the heating efficiency of the flames. The longitudinal axes of the cutting oxygen passage 42 and the combustible gas passage 43 are substantially in a common plane with the center of curvature of the curved portions which discharge into the inlet end of the nozzle. The combustible gas passage 43 is farther from the aforementioned center of curvature than the oxygen passage 42 and is outside of and above the oxygen passage.

A groove 47 is formed in the surface of body 41, and when the molten metal forming shield S is poured about said body, the molten metal fills the groove 47 to form an inwardly extending lip 48. The groove 47 and lip 48 interfit so that shield S is mechanically and permanently retained on the body. The groove 47 need not be continuous or as extensive as shown, but may comprise a plurality of short grooves or indentations, so positioned that the short lip sections will interfit therewith and hold the shield in place. A slot 49 may be formed in the shield S to reduce the weight of the head.

While I have described and illustrated different embodiments of my invention, it will be apparent to those skilled in the art that various modifications may be made without departing from the spirit and scope of the invention as set forth by the claims.

70 What is claimed is:

1. A blowpipe head comprising in combination, a body of machinable metal and thereby having relatively low wear resisting properties of generally elbow shape having at one end respective 75 inlets for oxidizing and fuel gases and at the

other end a socket disposed at an oblique angle to said inlets and adapted to be coupled to a blowpipe nozzle, said body having therein respective gas passages leading from said inlets to said socket for conveying gas to said nozzle; and an abrasion-resistant shield of relatively hard metal extending over the greater part of the area of the outer surface of said elbow shaped head and secured to portions of said body for protecting and reinforcing the same.

2. A blowpipe head comprising in combination, a body of machinable metal and thereby having relatively low wear resisting properties and being of generally elbow shape having at one end respective inlets for oxidizing and fuel gases and at the other end a socket disposed at an oblique angle to said inlets and adapted for operative connection to a blowpipe nozzle, said body having gas passages for conveying gas from said inlets through said socket to said nozzle; and an abrasion-resistant shield comprising a layer of relatively difficult to machine metal of substantially uniform thickness cast on and covering the greater portion of the outer elbow bend surface of said body between said gas inlets end and said nozzle socket end, said shield and the portion of said body in contact therewith being so shaped that said shield clings to and is permanently retained on said body.

3. A blowpipe head comprising in combination a body of machinable metal and thereby having relatively low wear resisting properties and being of generally elbow shape having at one end respective inlets for oxidizing and fuel gases and at the other end a socket disposed at an oblique angle to inlets and adapted to be coupled to a blowpipe nozzle, said body having therein passages for conveying gas therethrough extending from said inlets through said socket to said nozzle, at least one of said gas passages being close to a portion of the exterior elbow bend surface of said body; and an abrasion-resistant and reinforcing shield comprising a layer of hard surfacing and wear resisting metal of substantially uniform thickness secured to said body over such exterior elbow bend and gas passage adjacent surface portion between said gas inlets end and said nozzle socket end.

4. A blowpipe head comprising in combination a metal body of machinable metal and thereby having relatively low wear resisting properties and being of generally elbow shape having at one end respective inlets for oxidizing and fuel gases and at the other end of a socket disposed at an oblique angle to said inlets and adapted to be coupled to a blowpipe nozzle, said body having therein gas passages for conveying gas from said inlets through said socket to said nozzle; an abrasion-resistant metal shield comprising a layer of hard surfacing material of substantially uniform thickness covering the greater portion of the exterior elbow bend surface of said body between said gas inlets end and said nozzle socket end; and means extending through said body transversely to the plane of its elbow bend and connecting portions of said shield for retaining said shield on said body.

5. A blowpipe head comprising, in combination, a body of machinable metal and thereby having relatively low wear resisting properties and being of generally elbow shape having at one end respective inlets for oxidizing and fuel gases and at the other end a socket disposed at an oblique angle to said inlets and adapted to be coupled to a blowpipe nozzle and having at least

one groove formed in the outer surface thereof, said body having therein gas passages for extending therethrough from said inlets through said socket for conveying gas to said nozzle; and

5 an abrasion-resistant shield comprising a layer of hard surfacing metal of substantially uniform thickness extending over the outer elbow bend surface of said body between said gas inlets end and said nozzle socket end thereof and extending

10 part way around said body and having a portion projecting into said groove whereby said shield is mechanically retained on said body.

6. A blowpipe for thermochemically removing metal from the surface of metal work, comprising, in combination, a deseaming nozzle having an axial gas passage therethrough; a body of machinable metal and thereby having relatively low wear resisting properties and being of generally elbow shape having at one end respective inlets

15 for oxidizing and fuel gases and at the other end a socket disposed at an oblique angle to said inlets and coupled to and holding said nozzle, said body having gas passages extending therethrough from said inlets through said socket for supplying

20 gas to said nozzle; a shield comprising a layer of relatively hard metal of substantially uniform thickness secured externally to said body and extending over the greater portion of the external elbow bend surface thereof between said gas inlets end and said nozzle socket end for protecting

25 and reinforcing the same, said shield having an arcuate flange adjacent said nozzle socket end extending around said body transversely to the plane of said elbow bend and adapted to contact

30 such work surface, such contacting flange extending substantially radially with respect to said axial gas passage and outwardly for a dimension greater than the maximum radius of the surface of said nozzle that when the end of said

35 nozzle and said contacting portion are both touching said work surface no parts of the nozzle therebetween will contact the work and the main axis of the gas passage of the nozzle will be disposed at a desired acute angle to such work surface.

7. In a deseaming blowpipe, in combination, a deseaming blowpipe head of machinable metal and thereby having relatively low wear resisting properties and being of generally elbow shape having at one end respective inlets for oxidizing and fuel gases and at the other end a socket disposed at an oblique angle to said inlets, said body having therein respective gas passages leading

50 from said inlets to said socket; an external protecting shield comprising a layer of substantially uniform thickness of wear-resistant metal extending over the outer elbow bend surface of said body between said gas inlets end and said

55 socket end; and a deseaming nozzle mounted in said socket and thereby coupled to said head and having a collar of wear-resistant metal, both said shield and said collar projecting beyond the adjacent portions of said head and all portions

60 of said nozzle therebetween to engage the surface of metal work for correctly positioning said blowpipe relative to said surface for deseaming use and cooperating to protect against excessive wear portions of said head and said nozzle adjoining

65 said shield and said collar.

8. For use in a blowpipe for cutting or deseaming ferrous metal, a blowpipe head of machinable metal and thereby having relatively low wear resistant qualities and being of generally elbow

70 shape having at one end respective inlets for oxi-

dizing and fuel gases and at the other end a socket disposed at an oblique angle to said inlets, said body having therein respective gas passages leading from said inlets to said socket, one of said passages comprising a cutting oxygen passage provided with a curved portion constructed and arranged to gradually change the direction of oxygen flow through said head passage; and an abrasion-resistant shield comprising a layer of substantially uniform thickness of relatively hard metal extending over the outer elbow bend surface of said body between said gas inlets end and said socket end and secured to portions of said body for protecting and reinforcing the same, said shield having an external portion curved similarly to said passage in the plane of curvature and thereby uniformly spaced from said passage.

9. A blowpipe head comprising in combination, a body of machinable metal and thereby having relatively low wear resisting properties and being of generally elbow shape having at one end respective inlets for oxidizing and fuel gases and at the other end a socket disposed at an oblique angle to said inlets adapted to receive a blowpipe nozzle, said body having therein respective gas passages leading from said inlets through said socket to said nozzle, the rear portion of said body being formed with flat side walls; and an abrasion-resistant shield comprising a layer of relatively hard metal generally U-shaped in cross section so that the portion corresponding to the bend of the U covers the front elbow bend surface of the body between said gas inlets end and said nozzle socket end thereof, while the parts corresponding to the limbs of the U extend over portions of said flat side walls.

10. A blowpipe head comprising, in combination, a body of machinable metal and thereby having relatively low wear resisting properties and being of generally elbow shape having at one end respective inlets for oxidizing and fuel gases and at the other end a socket disposed at an oblique angle to said inlets and adapted to receive a blowpipe nozzle, said body having therein respective gas passages leading from said inlets to said socket, the rear portion of said body being formed with flat side walls; and an abrasion-resistant shield comprising a layer of relatively hard metal of substantially uniform thickness extending over the outer elbow bend of said body between said gas inlets end and said nozzle socket end and secured to said body, said shield having an outwardly projecting lip or shoe extending at least part way around the lower end of the head adjacent the nozzle socket.

11. For use in a blowpipe for cutting or de-seaming ferrous metal, a blowpipe head of machinable metal and thereby having relatively low wear resisting properties and being of generally elbow shape and having a gas passage therein provided with an inlet portion and an outlet portion disposed at an angle to each other, said inlet portion being adapted to receive cutting oxygen and said outlet portion being adapted to receive a cutting or de-seaming nozzle; and an abrasion-resistant shield comprising a layer of hard surfacing metal of substantially uniform thickness cast on and covering a portion of the outer elbow bend surface of said body between said inlet and outlet portions; said gas passage, said outer surface, and said shield being similarly curved to provide substantially uniform wall thicknesses in the plane of curvature, whereby a streamlined exterior for said head and a smooth flow for said passage are provided.

12. For use in a blow pipe for cutting or de-seaming a ferrous metal, a blowpipe head of machinable metal and thereby having relatively low wear resisting properties and being of generally elbow shape and having a cutting oxygen passage and a fuel gas passage therein provided with respective inlet portions and outlet portions disposed at the same angle with each other, said inlet portions being adapted to receive cutting oxygen and fuel gas respectively, and said outlet portions being adapted to receive a cutting or de-seaming nozzle, said fuel gas passage comprising a substantially straight bore connecting its inlet and outlet portions; and an abrasion-resistant shield comprising a layer of hard surfacing metal of substantially uniform thickness cast on and covering a portion of the outer elbow bend surface of said body between said inlet and outlet portions; said gas passage, said outer surface, and said shield being similarly curved to provide substantially uniform wall thicknesses in the plane of curvature, said shield and the portion of said body in contact therewith being so shaped that said shield clings to said body; and means passing through said body between said curved and straight passages and connecting portions of said shield for permanently retaining said shield on said body.

13. In a de-seaming blowpipe for removing metal from a surface of a ferrous metal body, in combination, a head formed of material having relatively low wear resisting properties and being of generally elbow shape and having fuel gas and oxygen passages extending therethrough, and the material of said head forming a wall between one of said passages and an outer surface of said head; a nozzle coupled to said head and having an oxygen passage extending longitudinally therethrough and communicating with the oxygen passage in said head; and a wear-resistant shield comprising a layer of hard surfacing material of substantially uniform thickness extending over and permanently secured to said outer elbow bend surface of said head to protect and reinforce said wall; said shield and said nozzle severally having work-contacting portions extending beyond all portions of said nozzle therebetween and adapted to simultaneously contact the surface of a metal body and, when simultaneously in such contacting position, cooperating to position the outlet orifice of such nozzle oxygen passage relative to the surface of a metal body.

14. In a de-seaming blowpipe for removing metal from a surface of a ferrous metal body, in combination, a head formed of material having relatively low wear resisting properties and being of generally elbow shape and having fuel gas and oxygen passages extending therethrough, and the material of said head forming a wall between one of said passages and an outer surface of said head; a nozzle coupled to said head and having an oxygen passage extending longitudinally therethrough and communicating with the oxygen passage in said head; and a wear-resistant shield comprising a layer of hard surfacing material of substantially uniform thickness extending over and permanently secured to said outer elbow bend surface of said head to protect and reinforce said wall; a wear-resistant flange on said shield and a wear-resistant flange on said nozzle extending beyond all portions of said nozzle therebetween and adapted to simultaneously contact the surface of a metal body and, when simultaneously in such contact-

ing position, cooperating to position the outlet orifice of such nozzle oxygen passage relative to the surface of a metal body.

15. In a deseaming blowpipe for removing metal from a surface of a ferrous metal body, in combination, a head formed of material having relatively low wear resisting properties and being of generally elbow shape and having fuel gas and oxygen passages therethrough, and the material of said head forming a wall between said oxygen passage and the outer surface of said head; a nozzle coupled to said head and having an oxygen passage extending longitudinally therethrough and communicating with the oxygen passage in said head; and a wear-resistant shield conforming to and reinforcing all of the outer surface of said wall of the oxygen passage in said head.

Certificate of Correction

Patent No. 2,510,227

June 6, 1950

WILGOT J. JACOBSSON

It is hereby certified that errors appear in the printed specification of the above numbered patent requiring correction as follows:

Column 7, line 36, before the word "inlets" insert *said*; line 54, after "end" strike out "of";

and that the said Letters Patent should be read with these corrections therein that the same may conform to the record of the case in the Patent Office.

Signed and sealed this 19th day of September, A. D. 1950.

[SEAL]

THOMAS F. MURPHY,
Assistant Commissioner of Patents.
